ASH RECEIVER

Edward F. McDonald, Buffalo, N. Y.

Application November 3, 1934, Serial No. 751,372

11 Claims. (Cl. 131—51)

This invention relates to smokers' appliances and particularly to an ash receiver. The present invention provides an improved, yet simple, ash receiver in which a receptacle is provided with an opening at the top normally closed by a pair of plate sections mounted in the receptacle for rocking movement, one of the sections being provided with an actuating member adapted to engage the other section in operation for actuating both sections and rocking them into an open position for discharging refuse into the receptacle. The actuating member for the pair of sections is fixed to one section and formed with a curved portion to engage the surface of the other section for rocking the other section in the rocking movement of the first section. This member projects above the section into a convenient position for normal actuation and may be formed with other portions adapted to cooperate with the other section to limit the rocking movement of both sections. The plate sections are further provided with means for normally retaining them in closed position on the receptacle where they are supported in substantially co-planar relation for cooperation in closing the opening in the receptacle. Suitable means may be provided in the form of weights or springs if desired for the purpose of normally retaining the sections in the closed position.

The invention comprehends the provision of a receptacle structure having a detachable top member provided with a depending inner wall portion defining the opening into the receptacle and forming a means for supporting the pair of plate sections normally closing this opening. The plate sections and the depending wall portion on the top member cooperate to provide a shallow tray in the top of the receptacle for receiving and supporting cigarettes, cigars and the like and receiving the ashes. The actuating member is projected upwardly from one of these sections and upon operation rocks the plate sections in opposite directions so as to discharge the contents of the tray portion at the top into the receptacle. The actuating member for the plate sections may be made in various sizes and shapes for enhancing the appearance of the receptacle which in numerous instances improves the efficiency as well as enhancing the appearance of the device.

In the drawing:

Fig. 1 shows the invention in perspective.

Fig. 2 is a vertical cross section through the ash receiver with the plate sections shown in open position.

Fig. 3 is a horizontal cross section taken on line 3—3 of Fig. 2, through the lower portion of the ash receiver looking upwardly at the bottom of the plate sections in open position.

Fig. 4 is a view similar to Fig. 2 showing the addition of resilient means to the receptacle structure for normally moving the plate sections into closed position.

Fig. 5 is a horizontal cross section similar to Fig. 3 looking upwardly at the bottom of the plate sections in open position and showing the operating spring for moving the plate sections to closed position.

The ash receiver comprises a receptacle having side wall portion 1 formed of a tubular sheet metal section provided with a bottom wall 2 secured to the sides 1 in any suitable manner. While the structure is shown in the form of a cylindrical receptacle, it may be made in any other desired shape. The sheet metal used to form the side wall portion 1 is formed at the upper edge of the receptacle to provide an inwardly extending flange 3 defining the opening in the upper end of the receptacle and at diametrically opposite points this flange is provided with cut-out portions 4. A top member 5 formed of sheet metal is mounted on flange 3 and has an annular top flange 6 seated on top of flange 3 and at the inner edge is formed a depending wall portion 7 extending through the opening in flange 3 into the receptacle. Wall portion 7 is formed with an inturned edge forming a seat 8 around the opening through the top member. Projections 9 are formed in depending wall portion 7 at diametrically opposite points to project outwardly for the purpose of engaging under the inner edge of flange 3 to lock the top member on the receptacle.

The top member may be engaged and disengaged from the receptacle by turning until the projecting portions register with cut-out portions 4 in flange 3.

A pair of plate sections 10 and 11 respectively, formed of sheet metal, are arranged to provide a closure for the opening into the receptacle through the top member. In the shape of the receptacle as illustrated in the drawing, these plate members are made in semi-circular form, each having one straight edge arranged in abutting relation when the plate members are in their closed position as illustrated in Fig. 1. In this closed position the plate members are in substantially co-planar relation so as to cooperate to close the opening in the top member. The circular margins of plate sections 10 and 11 are adapted to rest on seat 8 at the lower end of depending wall portion 7.

These plate sections are formed with projections 12. The axis of projections 12 on each plate section is parallel to the straight edge of the section and spaced from said straight edge in the structure as illustrated about one-half inch. These projections 12 extend through openings 13

in the bottom portion of depending wall portion 7 and mount the plate sections in the top member for rocking movement. The axis on which each plate section rocks is in spaced parallel relation to the axis of the other plate section and about an inch apart as clearly illustrated in the drawing and so arranged that when the plate sections are in co-planar relation, the straight edges will abut one another and close the opening in the top member. These plate sections are located in their closed position at the lower end of depending wall portion 7, resting on seat 8.

An actuating member 14 is mounted on the upper face of section 10 as illustrated in the drawing by means of suitable screws or the like 15. This actuating member projects laterally and upwardly from section 10 to form a means by which both sections may be rocked on their pivots or projections 12. Actuating member 14 is located so that one edge is adjacent the straight edge of section 10 on one end portion thereof. A rounded or curved portion 16 on actuating member 14 overhangs the adjacent edge of section 11. A handle portion 17 on the actuating member may be manually engaged for rocking plate 10 on its pivots or projections 12 so as to tip the plate from the position shown in Fig. 1 to the position shown in Fig. 2. Simultaneous with this tipping movement of section 10 rounded portion 15 of actuating member 14 will engage the adjacent portion of section 11 on its upper face and at a point adjacent to the straight edge. As actuating member 14 is rocked from the position shown in Fig. 1 to that shown in Fig. 2 this rounded portion 16 will cause section 11 to rock on its pivots 12 in a direction opposite to section 10 and into the position shown in Fig. 2. A corresponding amount of rocking motion of section 11 is obtained in the operation of actuating member 14 to the rocking of section 10 so that in any position both sections are tilted approximately the same amount as clearly illustrated by the position of the sections 10 and 11 in Fig. 2.

As soon as pressure on actuating member 14 is released the parts will return from the position of Fig. 2 to that shown in Fig. 1 where the opening in the top member will be closed. This return movement is obtained by gravitational action due to the weight of the members 10 and 11 along their semi-circular edges being greater than the weight on the opposite side of the axis formed by projections 12 and along the straight edge. The actuating member secured to section 10 does not hinder the return movement of sections 10 and 11 to the normal closed position but assists to make the movement of both sections uniform. For the purpose of returning plate sections 10 and 11 to the normal closed position faster than their own weight can provide, these sections may be provided at points on the semi-circular edge portion outermost from the pivot axis, with weights 18. These weights are also found to aid in deadening the noise produced by the plates engaging seat 8 as they move into closed position. In this way the operation of the plates is made quiet. This quieting of the operation of the plates may also be improved by coating the under faces of the plates with any suitable composition or by other suitable means designed for the purpose.

Actuating member 14 in the form illustrated in the drawing has a configuration simulating a duck and handle portion 17 forms the duck's head and is provided with a projection 19 forming the duck's bill that acts as a stop to engage

plate section 11 when the parts are moved into the position of Fig. 2. The tilting movement of plate sections 10 and 11 in opposite directions is therefore limited.

The tilting of the plates sufficiently to dump 5 ashes, cigarettes, etc. deposited on the top of the plate sections into the receptacle is secured in a simple and convenient manner by member 14. Cigarette and cigar stubs may be deposited in the receptacle when the plates are in the open position of Fig. 2 either between the plates or on the outside of the plates through the opening in the top member on either side of the outer edges of the sections as shown in Fig. 2.

It may be desirable instead of operating plate 15 sections 10 and 11 by means of weights 18 to provide other means of positively rocking the plates from the open position to the closed position. In Figs. 4 and 5 the top member is shown provided with a leaf spring 20 secured in any suitable manner as indicated at 21 to depending wall portion 7 while the opposite end 22 is engaged with the under side of plate section 11 adjacent to the straight edge portion and immediately under the portion engaged by curved portion 16' of actuating member 14' as clearly illustrated in Fig. 5. This spring presses upwardly and serves to actuate both sections 10 and 11, as its actuation of section 11 causes the upper face of section 11 to engage curved portion 16' of actuating member 30 14' and through the medium of the actuating member rocks section 10 on its pivot toward and into closed position. Spring 20 will effectively and normally retain sections 10 and 11 in closed position until actuating member 14' is manually engaged to actuate said plate sections into the open position as shown in Fig. 4.

Cut-out portions 4 in flanges 3 are made long enough to accommodate the projecting ends of projections 12 so that top member 5 may be 40 readily applied and secured in position on receptacle 1 and detachably retained thereon by projections 9.

Annular portion 6 of top member 5 is provided at 23 with a concave seat portion to provide a rest for cigarette or cigar. While only one of these rests or seat portions 23 is illustrated, more may be provided if desired at spaced intervals around annular portion 6.

From the foregoing description it will be appreciated that an exceedingly simple ash receiver has been provided by this invention that will contain and conceal ashes, stubs and other refuse. The actuating member 14 provides a means in combination with sections 10 and 11 for providing a closure for the open upper end of the receptacle that may be readily rocked into open position while actuating member 14 may be formed in any desired shape that is found useful for performing its purpose of actuating both sections 10 and 11 simultaneously.

For example, the actuating member 14' may be formed in the shape of a disc, providing a curved portion 16' overhanging plate section 11, as clearly shown in Fig. 4. The disc is mounted and operated in exactly the same manner as the actuating member 14. The tilting movement of sections 10 and 11 in opposite directions, in this instance, is limited by providing the disc with a diameter slightly greater than the distance between the pivots 12 on plate sections 10 and 11.

Actuating member 14 not only provides means for conveniently rocking sections 10 and 11 simultaneously but also for limiting their rocking movement in one direction, and preventing the 75

closing of plate section 11 without the closing of section 10. It further provides for convenient actuation of both plate sections 10 and 11 from the open to the closed position by any suitable 5 means actuating plate section 11.

Sections 10 and 11 further cooperate in their 10 location at the bottom of wall portion 7 with this wall portion and the top member to provide a tray at the top of the receptacle adapted to support cigarettes and cigars while they are being smoked either in the rest 23 or by laying the cigarettes or cigars on top of plate sections 10 or 11 and letting a portion overhang annular portion 6. This tray receives ashes wiped from the ends of 15 cigarettes or cigars, the inner edge of top member 5 at the upper end of wall portion 7 serving as a suitable wiping edge for this purpose. Ashes and stubs are readily dumped by actuating member 14 in the manner above described and as a result 20 a simple but efficient ash receptacle is provided that is economical to manufacture and efficient in operation.

The invention claimed is:

1. An ash receiver comprising a receptacle 25 formed with an opening and a closure for said opening having a pair of sections, means mounting said sections for rocking movement, and a handle member mounted on one of said sections adapted for manual engagement to rock said section 30 having a protuberance formed to engage the surface of and rock the other section.

2. An ash receiver comprising a receptacle 35 formed with an opening and a closure for said opening having a pair of sections, means mounting said sections for rocking movement, and an actuating handle member fixed on one section and formed with a projecting marginal portion spaced from the portion secured to the first mentioned section for cooperative engagement with 40 the surface of the other section for rocking said sections when said member is manually engaged and actuated.

3. An ash receiver comprising a receptacle 45 formed with an opening and a closure for said opening having a pair of sections, means mounting said sections for rocking movement, an actuating member fixed on one section and formed with a peripheral portion spaced from the portion engaging said section for cooperative engagement with an adjacent surface of the other section for rocking said sections when said member is manually engaged and actuated, and means 50 on said actuating member to engage said other section and limit said rocking movement.

55 4. An ash receiver, comprising a receptacle formed with an opening and a closure for said opening having a pair of sections, means mounting said sections for rocking movement, and an actuating member fixed on one section and 60 formed to engage the other section for rocking said sections in the actuation thereof, said actuating member being formed for cooperation with said sections to limit said rocking movement.

5. An ash receiver, comprising a receptacle 65 open at the top, a pair of sections mounted in the top of said receptacle for rocking movement, said sections normally cooperating to close the opening in the top of said receptacle, and an actuating handle member mounted on and projecting 70 upwardly from one section and formed to engage the surface of the other section for rocking both sections in the actuation thereof to open position for discharging refuse into said receptacle.

6. An ash receiver, comprising a receptacle, a top member mounted on said receptacle having an inner depending wall portion formed with a seat at the lower end defining an opening, a pair of plate sections normally cooperating in substantially co-planar relation to close said opening with the marginal portions engaged with said seat, said sections having extensions cooperating with said depending wall portion mounting said sections in the lower end of said wall portion for 10 rocking movement and an actuating member fixed on top of one of said sections operable to engage and actuate the other section whereby both sections may be manually rocked to open position by operating said actuating member. 15

7. An ash receiver, comprising a receptacle, a top member on said receptacle having an inner depending wall portion defining an opening, a pair of plate sections mounted for rocking movement in the lower portion of said depending 20 wall, said sections normally resting in co-planar relation and closing said opening, said sections and wall portion cooperating to form a tray portion at the top of said receptacle, and a member mounted on one section adapted to engage the 25 other section and projecting above the top of said receptacle for manual actuation to rock said sections and discharge the contents of said tray section into said receptacle.

8. An ash receiver, comprising a receptacle 30 having an opening and a closure for said opening having a pair of coplanar sections, means mounting said sections for rocking movement, and a member mounted on one of said sections formed with a curved portion for engaging the 35 surface of the other section whereby actuation of said member rocks both sections.

9. An ash receiver, comprising a receptacle 40 having an opening and a closure for said opening having a pair of sections, means mounting said sections for rocking movement, and a member mounted on one section having a curved portion for engaging and operating the other section in the actuation of said member, said member being adapted for manual operation to rock both sections, and another portion of said member 45 cooperating with said other section for limiting rocking movement of said sections.

10. An ash receiver comprising a receptacle 50 having an opening and a closure for said opening having a pair of sections, means mounting said sections for rocking movement, an actuating handle member fixed on one section and formed for cooperative engagement with the surface of the other section for rocking both sections 55 in opposite directions when manually engaged and actuated, and means for normally and positively actuating said sections in the opposite direction.

11. An ash receiver comprising a receptacle 60 having an opening and a closure for said opening having a pair of sections, means mounting said sections in coplanar relation for rocking movement, an actuating member fixed on one section formed to engage the surface of the other section for rocking both sections in opposite directions in the actuation thereof, and resilient means for normally actuating said sections in the opposite direction into cooperative co-planar relation. 65 70

EDWARD F. McDONALD.
